UNITED STATES PATENT OFFICE

LEWIS E. LEIGH, OF NORTHAMPTON, MASS., ASSIGNEE OF TWO-THIRDS TO
JOHN N. LEONARD AND LUTHER J. WARNER, BOTH OF SAME PLACE.

FLIER FOR SPINNING-MACHINES.

SPECIFICATION forming part of Letters Patent No. 356,229, dated January 18, 1887.
Application filed June 5, 1886. Serial No. 204,207. (No model.)

To all whom it may concern:

Be it known that I, LEWIS E. LEIGH, residing at Northampton, in the county of Hampshire and State of Massachusetts, have invented certain new and useful Improvements in Fliers for Spinning-Machines, of which the following is a specification, reference being had therein to the accompanying drawings.

This invention relates to fliers for spinning to frames.

The invention consists in the improved construction of the flier and the combination of parts which form the same, the object being to produce a flier which is well balanced and easy of adjustment.

In the drawings, Figure 1 is an elevation of the flier applied to a broken spindle. Fig. 2 is a top plan of the flier. Fig. 3 is a central vertical section of the flier. Fig. 4 is an elevation, part being broken away. Fig. 5 is a plan or end view of button D.

It will be understood that the spindle R, bobbin S, and whirl T are of usual construction.

The flier consists of a wooden body, A, having a central passage, a, for the spindle, the guard, B, formed of a wire and having a loop, b, at its top, and the arms C C, which are continuations of the wire forming the guard, and terminating in loops or eyes c c. The body A is a hollow cylindrical shell having a removable end piece, a', and a fixed end piece, a'', the ends being perforated with holes a little larger in diameter than the spindle at the point where the flier is to be attached.

Between the ends or heads a' a'' there is a chamber, a', of greater diameter than the openings in the heads. In this chamber the open button D is placed. This button is a little less in diameter than the chamber a', and a little less in thickness than the chamber a', and a little between the ends or heads a' a''. The button D has a central perforation, preferably slightly tapered and of such size as to bind closely to

the spindle. The body A is thus free to move slightly in all directions independently of the movement of the button D, which button will partake of the movement of the rotary spindle R when the flier is properly applied thereto. A single wire bent to proper shape, as clearly shown in Fig. 3, constitutes the guard constituting the arms. The lower ends of the wire connecting the arms. The lower ends of the wire connecting the arms pass through small holes e e in the body A, and below the said body these ends are curved upwardly and outward and then bend down and terminate in loops c c.

The head a' may be secured in its position in the body by pin i, or in other possible manner. The strand from the b passes through one of the eyes c, then the b and through the loop b of the guide, then the receiving spool, in usual manner, means of the two arms C C the flier advanced, and as the loops c rapidly opposed loop may be used when one of and to rock slightly on button The freedom of the flier to turn independent of steady movement to the flier and from liability to work by "jerks."

I claim—

1. A flier for spinning frames, a cylindrical body with central chamber having a perforation, a button guard, B, having a perforation in the body of C, terminating in eyes c c, said formed of a single wire, sub

scribed.

2. The combination, with flier body A, having removable button D, which

spindle, substantially as c in presence of two witne
